SULFITE HAIR WAVING COMPOSITION COMPRISING A NITROGEN-CONTAINING COMPOUND AND A SUBSTITUTED AROMATIC COMPOUND AS ADDITIVE, AND METHOD OF USE

Paul C. Watson, North Quincy, Mass., assignee to Arthur D. Little, Inc., Cambridge, Mass., a corporation of Massachusetts

Application May 27, 1954, Serial No. 432,710

7 Claims. (Cl. 167—87.1)

This invention relates to the treatment of hair, and more particularly to the treatment of hair to cause it to conform to a predetermined configuration, which configuration will return upon drying after repeated wetting with water.

So-called "cold waving" of hair has been practiced for several years with considerable consumer acceptance. The basis of all of the successful cold waving formulations to date is the incorporation of a thioglycolate therein. Considerable speculation and research work has been directed to the determination of the action of this compound, but it is believed that the precise mechanism has not been finally determined. The process employed for waving hair consists, generally, in applying the treating agent to the hair, wrapping the hair in curlers, allowing the treatment to continue for the desired length of time (usually less than one hour) removing the treating agent, by destroying it as by oxidation, or by washing it out with water, and drying the hair. The curlers are removed before washing.

Many careful studies have shown that thioglycolic acid and ammonium thioglycolate tend to damage hair and skin by prolonged or repeated treatment. This damage is more pronounced on hair which has been bleached or dyed. The odor of thiols in general, is objectionable, and thioglycolic acid and ammonium thioglycolate are no exception. The disagreeable odors of the thioglycolates has made it undesirable and impractical to make a hair preparation which could be applied to wave, straighten, or train hair without curlers and which could be applied and left on the hair over a period of time. The lack of odor of the preparation in this invention, on the other hand, permits it to be so applied and retained on the hair over a period of time. Thus, in summary, the cold wave preparations available until now have the disadvantage of the possibility of hair damage, disagreeable odor, and incapability of being used as a hair treatment to be left on the hair for a period of time.

Soluble sulfites, including sodium bisulfite, have been employed as hair treating agents, but their action is so slow at room temperature as to preclude their use as the cold waving agent.

Other agents and combination of agents have been employed for waving hair at room temperature, but they are either too severe in their action, or have other disadvantages, such as unpleasant odor. It is known that ammonium sulfide and thioglycerol wave hair well, but they are toxic.

It is to be understood that the term "hair treating," as hereinafter used, includes curling or waving, straightening, training and any other treatments which give the hair desired configurations.

It is an object of this invention to prepare a hair treating composition which can be effectively employed at room temperature.

Another object is to prepare a hair treating composition which acts more rapidly than the so-called cold wave com-

2

positions now employed. This is accomplished by the use of an additive.

Still another object is to prepare a hair treating composition which is substantially odorless.

5 A further object is the preparation of a hair treating composition which damages hair less than those now in use.

Still another object is to prepare a hair treating composition which exhibits less "wash-out," i. e., retains the 10 curl over a larger number of washings.

Another object is to prepare a solution which readily swells hair at room temperature thereby rendering the hair amenable to permanently setting it in a predetermined configuration.

These and other objects, will become apparent hereinafter.

Hair is composed of keratin, and keratin is largely made up of relatively long chain polyamides cross linked by disulfide linkages. In the waving of straight hair, or 20 the straightening of curled hair, it is necessary first to break the disulfide linkages and then to swell the thus modified fiber. I have found that a soluble bisulfite such as an alkali metal bisulfite, is particularly useful for this purpose. Sodium bisulfite and sodium metabisulfite, 25 $\text{Na}_2\text{S}_2\text{O}_5$ (which hydrolyzes in the presence of water to yield NaHSO_3) have been found to be particularly effective.

As in any setting operation, the swelled and chemically reduced fiber is placed in the predetermined position desired, and the reducing agent is neutralized with an oxidizing agent, such as potassium bromate; the resulting product and the swelling agent are removed by washing with water. The fiber so set, permanently assumes the altered shape and remains thus fixed indefinitely.

35 In accordance with this invention, I provide a composition comprising a mixture of a water-soluble sulfite as the agent for breaking the disulfide linkages, as a swelling agent a water-soluble nitrogen containing compound of the amide or imide class and an additive chosen from a group of polyfunctional aromatic compounds of the proper concentrations and the proper pH and a method of applying the composition to the hair. This serves as an excellent hair treating formulation in that it permits training hair or setting it to a desired configuration in a 45 short period of time without the use of solutions having undesirable odors or harmful effects on the hair.

The sulfite introduced into the mixture may be most conveniently a bisulfite, such as sodium bisulfite, sodium metabisulfite (which hydrolyzes in the presence of water to yield sodium bisulfite), potassium bisulfite, ammonium bisulfite, or an amine bisulfite, such as normal propyl amine bisulfite.

50 The amide or imide must be water-soluble to the extent that at least about 15% of the weight thereof required in the composition of this invention is soluble in the water content of the composition.

Among the amides and imides which are suitable nitrogen-containing components are the mono-, di- and tri-ammonia substituted analogs of formic acid, their esters, and their alkyl and alkanol substituted derivatives. These 55 analogs are those derived by displacing one or more of the three substituents on the carbon atom of formic acid with ammonia. The ester group may be attached through the hydroxyl group of the formic acid molecule. The alkyl and alkanol substituents are desirably substituted in place of the hydrogen atom of formic acid, although they may be substituted on the ammonia substituents. The alkyl and alkanol substituents should not exceed four carbon atoms when taken together. In the case of guanidine, 65 which is the tri-ammonia analog of formic acid, it is preferable that there be no further substituents on the compound.

Some of the particularly effective nitrogen-containing components for the purpose of the present invention may be defined as those represented by the formula

wherein X is a member of the group consisting of hydrogen, alkyl and alkanol radicals containing not more than three carbon atoms, the radical

wherein n is the integer one or two, $-NR_3R_4$, and OR, wherein R is an alkyl radical containing not more than three carbon atoms. The groups R_1 , R_2 , R_3 and R_4 are members of the class consisting of hydrogen, alkyl and alkanol groups which when taken together shall contain not more than four carbon atoms. Z is either oxygen or $=NH$, but preferably oxygen. Examples of such nitrogen-containing components are acetamide, ethanol formamide, diethanol formamide, monoisopropanol formamide, ethyl formamide, formamide, dimethyl formamide, N-mono-ethyl acetamide, n-propionamide, n-butyramide, urethane, guanidine, ethanol urea, methyl urea, urea and the amides and imides of dibasic acids containing not more than five carbon atoms, such as succinimide and malonamide.

The pH of the mixture is important, and the effective pH range is between 6 and 7.5 while the better range is between 6 and 7 and the preferred pH is 6.8. If the pH exceeds about 7.5 or 8, the wet curl retention drops materially, and if it is above 9, the action of alkali becomes harmful.

The concentration of both sulfite and amide is also important. The most effective range for sulfite, based on the SO_2 content by weight, is from 2.0% to 10% of the total composition, while the preferred range is from about 5% to 7.0%. The most effective range of the amide is from 15% to 40%, and the preferred range from 20% to 35%, although about 30% has been found to be the optimum concentration. The desired pH may be obtained by adding an alkali such as NaOH or by using a mixture of sodium sulfite and sodium metabisulfite in the proper proportions.

The concentrations of the sulfite and amides are, however, directly dependent upon each other, thus making it inadvisable to choose concentrations from each of the ranges stated without giving consideration to the over-all concentration of the solution. Thus, if high concentrations of amide are used along with the higher limits of sulfite, an exceptionally effective hair setting or treating solution is formed, but the amide might salt out and crystallize on the hair. Thus, the combined solubility of these components at room temperature (or slightly below) becomes an important factor in the determination of concentrations, for it is undesirable that there be any solids present at normal room temperatures in a hair treating solution. Generally, as the amide concentration is increased, the sulfite concentration must be decreased. Using urea and sodium metabisulfite ($Na_2S_2O_5$) as an example, it has been found that the concentrations listed below are the most effective at 25° C. and at a pH of 6.8.

Percent by weight of Urea	Percent by weight $Na_2S_2O_5$	SO_2 equivalent weight ¹
20	15	10.1
30	6 to 12.5	4 to 8.4
40	3 to 9	2 to 6.1

¹ 67.3% of $Na_2S_2O_5$ weight.

The preferred nitrogen-containing components include formamide, $HCONH_2$; urea, H_2NCONH_2 ; urethane,

$C_2H_5OCONH_2$; and acetamide, CH_3CONH_2 , and will hereinafter be referred to as the amide component.

Although compositions of the type and ranges discussed above are effective hair treating solutions, they are relatively slow and dependent upon temperature. The reaction time of these compositions of sulfite and amide may, however, be speeded up materially by the use of a small quantity of an additive. The reasons for the marked improvement in hair treating brought about by the use of an additive is not known, but thirty-minute waving efficiencies up to 74% have been attained with additives as compared for 48% for a similar composition without an additive.

Additives which have been found satisfactory for the compositions of this invention are substituted aromatic compounds such as pyrocatechol, p-methyl aminophenol sulfate, phenyl hydrazine, gentisic acid, 1-hydroxy-2-naphthoic acid, gallic acid, anthranilic acid, benzilic acid and salicylic acid.

Some of the particularly effective additives for the purpose of the present invention may be defined as those represented as substituted aromatic hydrocarbons containing no more than two benzene rings and having two or more substituents taken from the group of OH, COOH, NH_2 , substituted NH_2 , C_6H_5 , and substituted C_6H_5 . Organic salts formed by the addition of inorganic acids to these substituted aromatics are also satisfactory. The choice of an additive from this group of substituted aromatics must, of course, be limited to those compounds which are not skin irritants and which are not toxic when applied externally in the percentage in which they are employed. It is preferable that the additive is not highly colored.

Among those additives suitable for the purposes of this invention, gentisic acid (2,5-dihydroxybenzoic acid, $(HO)_2C_6H_3COOH$) is preferred, while 1-hydroxy-2-naphthoic acid ($C_{10}H_6(OH)COOH$) is almost as effective.

Amide concentrations above 40% by weight have been found to have a deleterious effect on the hair, causing excessive swelling of the keratin of the hair. In fact, above about 40% amide concentrations, the damage to hair is so severe that hair waving compositions should be limited to concentrations below that figure.

Additive concentrations should not be lower than 0.5 nor exceed about 6% by weight of the components and should preferably be kept within the range between about 1 and 4% by weight depending upon the particular additive. The preferable concentration for gentisic acid, for example, is 2% while that for 1-hydroxy-2-naphthoic acid is 4%.

The amide may be premixed with the sulfite and additive and dispensed as a ready-made solution; concentrated solutions may be made up separately of the amide component and of the sulfite and additive mixed; or the amide may be bottled as a water solution and the remaining ingredients packaged as a dry powder. Since formamide mixed with sulfites has a tendency to lose its effectiveness as a component in the hair treating composition of this invention after storage, formamide-containing compositions should preferably be packaged in the third-named manner.

The temperature at which these solutions are used is limited usually to a range between room temperature, or slightly lower, and body temperature. This means a temperature range of about 20° to 30° C. Temperatures above body temperatures may conceivably be used up to a comfortable maximum, perhaps as high as 37-40° C. As the temperature increases, the effectiveness of the solution, in terms of wet curl retention, increases. At the higher concentration, the rate of increase in effectiveness is even more marked at high temperatures. The time of exposure of the hair to the solution depends upon the temperature used, the effectiveness of the particular solution and the degree of curl retention desired. Nor-

mal exposures are of the order of 30 to 90 minutes.

It is desirable to stop the action of the treating solution by the use of a "neutralizer." Such a neutralizer should be capable of removing the sulfite ion and must not, of course, be harmful to the hair or skin. Examples of neutralizers include water and mild oxidizing agents such as a dilute solution of perborate or alkaline bromate.

Experimental work has shown that the degree of curl retained permanently depends upon the amount of swelling imparted to the hair while wrapped on curlers and the degree to which the shrinkage of the hair is subjected by the oxidizing agent and subsequent removal of the compounds by washing. Unless the hair is swelled at least 18%, adequate permanent set cannot be obtained by the process of this invention. Swelling action far in excess of 18% may be readily secured. Hair varies in thickness and in chemical composition so that hair from different sources will swell to varying extents with a given treatment under identical conditions. The concentration of soluble bisulfite required to break the disulfide linkages and the concentration of the swelling agent required to impart a desired degree of swelling of hair also depends upon the quantity employed. In general, the swelling action increases with increasing concentration and as the pH of the mixture approaches 7.0. Under usual conditions encountered in hair waving sufficient swelling is obtained with 5% sodium bisulfite and 1% sodium bisulfite may be employed in some instances. The concentration of swelling agent must be sufficient to cause at least 18% swelling within one hour under the usual conditions, as stated above, but swelling in the order of 30% to 80% within one hour at room temperature is preferable for the usual treatment. Swelling of hair in excess of 80%, and particularly in excess of about 110%, requires care in its management since the hair becomes so greatly weakened that it may break if handled improperly.

The measure of the effectiveness of a hair waving solution is the degree to which the curl is retained after treatment. Thus, the minimum concentrations of amide and bisulfite are dictated by an acceptable degree of curl retention. Such minimum concentrations are about 15% amide by weight and about 2% SO_2 equivalent by weight. Below these concentrations, curl retention is very low.

Because curl retention is the important factor in making a desirable cold wave solution, a means for accurately measuring this property has been devised. The means are shown in Figs. 1-4.

Fig. 1 is a bundle of about 50 parallel strands of straight hair to be tested. Fig. 2 is a perspective view of a device for curling hair; Fig. 3 is the same view wherein the device is surrounded by a wetted web; Fig. 4 is a view of a typical flat curled swatch of hair, and Fig. 5 is a graph showing the marked decrease in hair damage achieved by the composition of this invention as compared with a typical thioglycolate solution.

A bundle of about 50 parallel strands of individual hairs, Fig. 1, is processed at a time. The bundle is combed so that the strands are parallel.

Referring now to Fig. 2, one end of the bundle 13 is bent over the end of waving-form 12 and attached as by an elastic band 14. The bundle is then bent around pegs 15, as shown, bent over the other end of waving form 12, and secured as with elastic band 16. After the hairs have been arranged on waving form 12, a narrow strip of blotting paper 17, as shown in Fig. 3, is wound around the pegs and held in place by an elastic band 18.

The blotting paper 17, is saturated with waving lotion, thus wetting the bands of hair and keeping them wet over the desired treating period. The whole form with the hair is then left at a fixed temperature for the time desired. After exposure to the waving solution for a specific length of time, the wave formed is immersed in water or in a neutralizer which may be a mild oxidizing compound, the straight ends of hair are cut at positions 21

and 22 on wave form 12, Fig. 2, and the entire bundle of hair springs is floated on water.

A value for what is termed "wet curl retention" is determined immediately after the hair is placed in the water and again after a specified length of time (generally thirty minutes). The bundle of hair is measured to obtain the length of the bundle of springs, usually the distance between the centers of the first and last, or next to the last, crests; for example, between the peak of crests 19 and 20, Fig. 4. This distance is compared with distance between the centers of the corresponding pegs of the waving form, and the result is called the "wet curl retention." This is calculated by the formula:

$$15 \quad 100 \times \frac{(L-l)-(L'-l)}{(L-l)}$$

where

L =drawn-out length of a strand of hair used to span the distance from the center of the two pegs selected 20 on the waving form;

L' =length of hair springs after curling measured from the center of the two crests corresponding to the centers of the two pegs selected on the waving form; and 25 l =distance between the centers of the two pegs chosen on the waving form.

Wet curl retention is taken as the true measure of the effectiveness of the waving solution, inasmuch as many substances, including water, will impart a curl which will be retained as long as the hair remains dry.

Fig. 5 illustrates the achievement of less damage to the hair by use of a typical composition of this invention. In Fig. 5 percent elongation is plotted against stress which was applied to a hair strand after subjection to a solution of 30% formamide, 8% $\text{Na}_2\text{S}_2\text{O}_5$, 0.5% gentisic acid (pH=7.0) for 30 minutes and subsequent neutralization with water. For example, at approximately the inflection point, about 7.5% elongation, around 1.38 gms./denier are required for hair waved with the formamide-sulfite-gentisic acid composition while only 0.93 gm./denier are required for hair waved with a typical thioglycolate solution. The added stress required is a measure of hair strength and thus a measure of decreased hair damage. Thus, the formamide-sulfite-gentisic acid composition of this invention shows a decrease in hair damage of about 48% over the commonly used thioglycolate composition.

This decreased hair damage shown by the sulfite-amide-gentisic acid composition is unexpected since it is known that with such compositions containing in excess of 40% amide, the protein in hair can be dissolved and destroyed. Thus, by the dilution of the composition to the ranges used in these hair treating compositions, the possibility of hair damage is reduced to below the now acceptable limits of the compositions currently in use. The reasons for this practical elimination of hair damage brought about through dilution are not known, but are clearly illustrated in Fig. 5.

The following examples are illustrative of the type of cold waving solutions which have been found to achieve the objects of this invention. This invention is not, however, limited by these examples.

EXAMPLE 1

A solution of 30% urea, 7.5% sodium metabisulfite 65 and 2% gentisic acid was made up in water and strands of hair subjected to this solution for 30 minutes by means of the waving form device described. Temperature was maintained at 25° C. and neutralization was done with water. Maximum wet curl retention, obtained at a pH of 6.8 (adjusted by adding NaOH), was 68% compared with 48% for the same solution without the gentisic acid.

EXAMPLE 2

A solution of 30% formamide, 10% sodium metabisulfite and 20% gentisic acid was made up in water and

strands of hair subjected to this solution for 30 minutes by means of the waving form device described. Temperature was maintained at 25° C., and neutralization was done with water. Maximum curl retention, obtained at a pH of 6.8., was 76%.

EXAMPLE 3

A solution of 30% urethane, 7.5% sodium metabisulfite and 3% 1-hydroxy-2-naphthoic acid was made up in water and strands of hair subjected to this solution for 30 minutes by means of the waving form device described. Temperature was maintained at 25° C., and neutralization was done with water. Maximum curl retention, obtained at a pH of 6.8., was 65%.

EXAMPLE 4

A solution of 40% acetamide, 5% sodium metabisulfite, and 2% gentisic acid was made up in water and adjusted to pH 7.0 with sodium hydroxide. Strands of hair were subjected to this solution for 30 minutes at 25° C. by means of the waving form device described. Neutralization was done with water. A curl retention of 50% was obtained.

A large number of additional composition containing additives were made up and evaluated in the manner described in Example 1. The improvements in 30-minute waving efficiency are shown in the tabulation below:

Additives to urea bisulfite formulations effect on hair treating efficiency at 25° C.

[Additives to 30% urea, 7.5% sodium metabisulfite at pH 6.8.]

Additive	Percent Additive	30-Minute Waving Efficiency, Percent
None—blank control		48
1,2-benzenediol	2	74
p-methyaminophenol sulfate	4	72
p-aminophenol HCl	1.5	72
p-aminoacetanilide	1	71
2,5-dihydroxybenzoic acid (gentisic acid)	2	68
1-hydroxy-2-naphthoic acid	4	67
p-amino salicylic acid	2	67
5-amino salicylic acid	2	67
3,4,5-trihydroxybenzoic acid (gallic acid)	1	66
O-aminobenzoic acid (anthranilic acid)	2	66
diphenylglycolic acid (benzilic acid)	0.5	65
O-hydroxybenzoic acid (salicylic acid)	6	62

I claim:

1. A liquid composition for setting hair in a predetermined configuration at temperatures between 20 and 40° C. without effecting any appreciable injurious swelling of said hair, consisting essentially of a water solution maintained at a pH between about 6 and 7.5 of a sulfite, a nitrogen-containing component and an additive, the combined solubility of which is such that no appreciable salting out of the components will occur on said hair at temperatures above about 20° C., said sulfite being present in a concentration equivalent to from about 2 to 10% by weight SO_2 of said solution, said nitrogen-containing component being present in a concentration equivalent to from about 15 to 40% by weight of said solution and having the formula

wherein X is a member selected from the group consisting of hydrogen, alkanol and alkyl radicals containing not more than 3 carbon atoms, the radical

wherein n is the integer selected from 1 and 2, —OR, wherein R is an alkyl radical containing not more than 3 carbon atoms, and —NR₃R₄, R₁, R₂, R₃ and R₄ being members of the class consisting of hydrogen, alkyl and alkanol radicals which when taken together shall contain

not more than 4 carbon atoms, and Z is a member selected from the class consisting of oxygen and =NH; said additive being present in a concentration equivalent to from about 0.5 to 6% by weight of said solution and being selected from the group consisting of substituted aromatic hydrocarbons and acid salts thereof, said substituted aromatic hydrocarbons having no more than two benzene rings and containing not less than two substituents taken from the group of OH, COOH, NH₂, substituted NH₂, C₆H₅, and substituted C₆H₅.

2. A liquid composition in accordance with claim 1 wherein said additive is gentisic acid.

3. A liquid composition in accordance with claim 1 wherein said additive is 1-hydroxy-2-naphthoic acid.

4. A liquid composition for setting hair in a predetermined configuration at temperatures between about 20 and 40° C. without effecting any appreciable injurious swelling of said hair comprising an aqueous solution of an alkali metal bisulfite, urea and gentisic acid, the pH of said composition being adjusted to between 6 and 7, said alkali metal bisulfite being present in a concentration equivalent to 3 to 6 percent SO_2 by weight of said solution, said urea being present in a concentration equivalent to from about 15 to 40% by weight of said solution and said gentisic acid being present in an amount equivalent to from 1 to 4 percent by weight of said solution, the combined solubility of said alkali metal bisulfite, said urea and said gentisic acid being such that no appreciable salting out will occur on said hair at temperatures above about 20° C.

5. A liquid composition in accordance with claim 4 wherein said alkali metal bisulfite is sodium metasulfite in a concentration of 7.5 percent by weight of said solution.

6. A liquid composition for setting hair in a predetermined configuration at temperatures between about 20 and 40° C. without effecting any appreciable injurious swelling of said hair comprising an aqueous solution of 10 percent by weight sodium metabisulfite, 30 percent by weight formamide and 2 percent by weight gentisic acid and having a pH of 6.8.

7. The process of permanently setting hair in a predetermined configuration without effecting any appreciable injurious swelling of said hair, comprising the steps of adjusting said hair to the desired configuration, contacting said hair for a period of from about thirty to ninety minutes maintained at a temperature between about 20 and 40° C. with a water solution of a sulfite, a nitrogen-containing component and an additive, the combined solubility of which is such that no appreciable salting out of the components will occur above about 20° C., treating said hair with a mild oxidizing agent, and washing said hair with water; said sulfite being present in a concentration equivalent to from about 2 to 10% by weight SO_2 of said solution, said nitrogen-containing component being present in a concentration equivalent to from about 15 to 40% by weight of said solution and having the formula

wherein X is a member selected from the group consisting of hydrogen, alkanol and alkyl radicals containing not more than 3 carbon atoms, the radical

wherein n is the integer selected from 1 and 2, —OR, wherein R is an alkyl radical containing not more than 3 carbon atoms, and —NR₃R₄, R₁, R₂, R₃ and R₄ being members of the class consisting of hydrogen, alkyl and alkanol radicals which when taken together shall contain

said additive being present in a concentration equivalent to from about 0.5 to 6% by weight of said solution and being selected from the group consisting of substituted aromatic hydrocarbons and acid salts thereof, said substituted aromatic hydrocarbons having no more than two benzene rings and containing not less than two substituents taken from the group of OH, COOH, NH₂, and substituted C₆H₅.
